CLAIM

The ornamental design for the tractor mounted device for lifting and unrolling hay bales, as shown and described.

DESCRIPTION

FIG. 1 is a perspective view of a tractor mounted device for lifting and unrolling hay bales showing my new design;

FIG. 2 is a top plan view thereof;

FIG. 3 is a rear elevational view thereof;

FIG. 4 is a front elevational view thereof;

FIG. 5 is a side elevational view as seen from the left side of FIG. 2; and,

FIG. 6 is a side elevational view as seen from the right side of FIG. 2.
